UNITED STATES PATENT OFFICE.

CHARLES BRENESSEL, OF LOS ANGELES, CALIFORNIA.

COLLAR ATTACHMENT.

Application filed September 12, 1927, Serial No. 218,899. Renewed September 17, 1928.

This invention relates to a collar attachment for preventing outward bending and curling of the collar points or front portions of the collar flap and an object of the invention, in general, is to provide an attachment of this character which, when in place on the collar, will prevent such outward bending and curling.

Another object is ease of attaching the device to the collar and detaching it from said collar.

Another object is inexpensiveness of manufacture.

A further object is to make a device of this character by a single punch press operation.

Other objects and advantages will appear in the subjoined detailed description.

The accompanying drawings illustrate the invention.

Figure 1 is a perspective view of a collar with two attachments, embodying the invention, applied thereto, said attachments being indicated in dotted lines as they are on the underface of the collar flap.

Fig. 2 is a view of the rear face of one of the front portions of the collar, with the attachment shown laid on the rear face of the flap in position for attaching to said flap.

Fig. 3 is a perspective view of the attachment.

Fig. 4 is a view similar to Fig. 2 showing one of the legs of the attachment flexed, so as to facilitate inserting of one of the penetrating members into the fabric of the collar.

Fig. 5 is an enlarged broken section on the line indicated by 5-5, Fig. 2.

Referring to the drawings, there is provided a stiff V-shaped body indicated in general by the character 6. The body 6 may be made of any springy stiff material such, for example, as strip spring metal. The connected legs of the body 6 are indicated at 7, 8 and, in this instance, the leg 7 is longer than the leg 8, though this difference in length is not absolutely necessary. The angle between the legs 7, 8 may be varied to conform with the outline of the collar flap to which it is to be secured and, in any event, the angle between said legs will be approximately the same as the angle between either of the front edges *d* of the collar flap *e* and the bottom edge of said flap, as is clearly shown in Figs. 1, 2 and 4

of the drawings, where the collar is indicated at *a*. The neck band of the collar *a* is indicated at *b*.

At the juncture of the legs 7, 8, the body 6 forms a pointed penetrating member 9, 60 and the legs 7, 8 form at their free ends, respectively, pointed penetrating members 10, 11. The penetrating members 9, 10, 11, in this instance, are of integral construction with the main portions of the legs 7, 8 and said penetrating members terminate at their bases in a shoulder or shoulders 12, which serve to limit the penetration of the legs 7, 8 into the fabric of the collar. In this instance, to produce the shoulders 12, the 70 penetrating members 9, 10, 11 have their bases narrower than the main portions of the legs 7, 8.

If the attachment is made of metal, it may, if desired, be provided with a coat 75 of enamel, not shown.

It is to be understood that two of the attachments 6 will be used with each collar, as indicated in Fig. 1. To secure one of the attachments to the collar, the following procedure may be adopted. The penetrating member 9 will be inserted into the fabric near one of the points *f* of the flap, and the leg 8 will then be flexed slightly and the penetrating member 11 inserted in the flap 85 in such position that the leg 8 will lie parallel with and close to the front edge *d* of the flap. The leg 8 will then be allowed to straighten, thus causing the fabric adjacent to the penetrating member 11 to engage the 90 associated shoulders 12. Then the leg 7 will be flexed slightly, as in Fig. 4, and the penetrating member 10 will be engaged with the fabric close to the bottom edge *e* of the flap in position to cause the leg 7 to lie substantially parallel with and close to the edge 95 *e*, and then the leg 7 will be allowed to spring into its natural position, thus causing the shoulders 12 adjacent to the penetrating member 10 to engage the fabric.

Then another of the attachments will be applied, in the same manner as described above, close to the other flap point *f*. The attachment will be removed by a reversal 100 of the above described operations.

Preferably, the leg 7 will be constructed so that the outer face thereof is slightly convex when said leg is in its natural position, as shown in Fig. 5. The advantage 105 of this is that the attachments, when in place

on the collar, will tend to bend the front portions of the collar flap inwardly toward the body of the person wearing the collar so as to neatly hold the front portions of the flap down close to the necktie or scarf.

5 I claim:

A collar attachment of the character described comprising two connected stiff legs forming a V-shaped body, the body forming

at the juncture of said legs a pointed penetrating member and the legs forming at their free ends other pointed penetrating members, and the penetrating members terminated at their bases by shoulders.

Signed at Los Angeles, Calif., this 4th day 15
of March 1927.

CHARLES BRENESSEL.
